APPARATUS FOR THE CUTTING OF SKIN GRAFTS

Edgar J. Poth, San Francisco, Calif., assignor to
The Board of Trustees of the Leland Stanford
Junior University, a body corporate of California

Application May 10, 1939, Serial No. 272,774

3 Claims. (Cl. 128—20)

This invention relates generally to instruments for the cutting of skin grafts, particularly grafts from the human skin.

It is an object of the invention to provide an improved instrument of the above character, which will be more practical than instruments heretofore available for this purpose, and which can be used with good results by the average technician.

10 A further object of the invention is to provide a retractor which will facilitate the cutting of skin grafts from different parts of the body, without interfering with the working space above the area from which the graft is taken.

15 Another object of the invention is to provide an improved form of knife for cutting skin grafts which can be readily adjusted for cuts of different thicknesses, which makes use of a novel blade assembly capable of renewal at a minimum 20 of cost without grinding, and which facilitates cutting grafts of large areas with a high degree of uniformity as to thickness.

25 Further objects of the invention will appear from the following description in which the preferred embodiment has been set forth in detail in conjunction with the accompanying drawings.

Referring to the drawings:

Fig. 1 is a plan view showing the parts of my retractor, and its method of application to the skin.

Fig. 2 is an enlarged detail showing the manner in which each retractor element is constructed, and is attached to the traction bar.

Fig. 3 is an enlarged detail, partly in cross-section, showing the manner in which the needle points are mounted in the retractor element.

Fig. 4 is a cross-sectional detail taken along the line 4—4 of Fig. 3.

Fig. 5 is a bottom plan view showing my adjustable cutting knife.

Fig. 6 is a top plan view of the same knife shown in Fig. 5.

Fig. 7 is a cross-sectional detail taken along the line 7—7 of Fig. 6.

Fig. 8 is a cross-sectional detail taken along the line 8—8 of Fig. 6.

Fig. 9 is an enlarged cross-sectional detail taken along the line 9—9 of Fig. 6.

Referring first to the retractor apparatus illustrated in Figs. 1 to 4 inclusive, it makes use of a pair of retractor elements 10, in conjunction with the traction bar 11. While the details of construction may vary, each retractor element has been illustrated as comprising a flat bar 12, 50 which is provided with spaced notches 13 for re-

ceiving the needles 14. A removable clamping plate 16 is carried by bar 12, and the removal of this plate enables the replacement or renewal of needles. The ends of bar 10 are attached to a yoke 17, which in turn is attached to the chain 18. The needles 14 are suitably spaced apart so that their points 19 can properly enter and grip the skin. Each yoke 17 is preferably bent at an angle as shown in Fig. 2, in order to tend to urge the needle points into the skin as tension is applied.

The traction bar 11 is substantially U-shaped as shown in Fig. 1, and its end portions 21 are provided with simple means of attachment to the chains 18. Thus in this instance studs or pins 22 are carried by the traction bar portions 21, and these pins may be engaged by any of the links of the chains 18, substantially as shown in Fig. 2. This form of attachment, together with the use of a chain or like flexible connection to the yokes 17, forms what may be termed an adjustable swivel connection.

Assuming that the two retractor elements are applied to the skin of a donor substantially as shown in Fig. 1, and the chains 18 attached to the traction bar so that a proper amount of tension is applied to the area of skin between the retractor elements, the working space above the stretched area of the skin is unobstructed. This is true irrespective of what portion of the body 30 the device is applied to, since the traction bar 11 may always be swung to an out-of-the-way position.

Although any knife may be utilized with the retractor apparatus described above, I prefer to make use of the adjustable form of knife illustrated in Figs. 5 to 9 inclusive. This knife comprises a frame 26, formed by the end blocks 27 and a blade assembly 28. The blade assembly includes a plurality of aligned safety razor blades 29 retained by the rigid mounting 31. Overlying the mounting 31 there is a bowed spring strip 32, the lower edge of which engages the safety razor blades and retains them in proper alignment upon the mounting 31. Strip 32 is supplemented by the inner element 33, for the same purpose. The inner edges of the safety razor blades 29 engage an abutment shoulder 34, whereby the cutting edges of the blades are brought into proper alignment. The shoulder 34 preferably has a slight curvature in the direction of its length, to insure a continuous cutting edge. The end portions of the mounting 31 are adjustably and removably attached to the frame as by means of bolts 35.

Attached to the blade mounting 31, there is a stationary depth guide bar 36, and at the forward side of the frame there is an adjustable depth guide 37. The latter is in the form of a flat rigid bar, with its ends slidably carried within grooves 38, formed in the blocks 27. In order to manually adjust the position of guide 37, I have shown a rod 39 extending through the frame, and with oppositely threaded portions 41. These threaded portions carry threaded blocks or nuts 42, whereby when rod 39 is turned by manipulating the end knobs 43, the nuts 42 traverse in opposite directions. Each nut 42 has a pivotal connection 44 with a link 46 and the other end of each link has a pivotal connection 47 with the depth guide 37. Thus the traversing of nut 42 by rotating rod 39, causes the depth guide 37 to be raised or lowered with respect to the frame. The nuts 42 are provided with tabs 48, for sliding engagement with the longitudinal stay rod 49.

As can be understood by reference to Fig. 8, when the knife described above is in use, the lower edges of the depth guides 36 and 37 engage the surface of the tensioned skin. Now by adjusting the forward depth guide 37, the depth of the cut can be accurately regulated.

For the convenience of an operator a handle 51 is attached to one end of the frame, and this handle can be removed and attached to the other end of the frame as indicated in dotted lines, for either right or left handed use.

The knife described above requires little experience for its proper use. It is particularly applicable in connection with retracting apparatus such as shown in Figs. 1 to 4 inclusive, because the knife works best with an evenly tensioned area of skin. By the use of my knife relatively large grafts can be taken with a high degree of uniformity as to thickness. The safety razor blades form a highly efficient cutting edge, which can be readily renewed by the simple expedient of applying new razor blades. It should be understood however, that a single blade of suitable length can be employed in place of the several safety razor blades.

I claim:

1. In apparatus for the cutting of skin grafts, a pair of retractor elements each provided with a row of needle points for engagement with the skin of a donor, a substantially U-shaped traction bar, and means forming single points of swivel connection between each of said retractor elements and the side branches of said traction bar, said points of swivel connection being adjustable to accommodate for varying distances between said retractor elements. 5

2. In apparatus for the cutting of skin grafts, a pair of retractor elements each provided with a row of needle points for engagement with the skin of a donor, a traction bar connected to said elements, said traction bar being adapted for disposition at one side of the skin area between said retractor elements, whereby to leave said area entirely free for both visual and manual access, and flexible connecting means between 15 each of said retractor elements and said traction bar whereby tension can be applied to said elements to apply tension to said skin area, said connecting means providing for varying lengths 20 between each of said elements and said bar whereby to selectively apply the desired amount of tension to said skin area. 25

3. In apparatus for the cutting of skin grafts, a pair of retractor elements each provided with a 30 row of needle points for engagement with the skin of a donor, a substantially U-shaped traction bar, and chains having single points of swivel connection between each of said retractor elements and the side branches of said traction bar, 35 the connection of said chains to said retractor elements and the associated side branches providing for adjustment of the respective lengths of the chains to accommodate for varying distances between said retractor elements as well as to 40 provide for application of the desired tension to the skin area between said retractor elements by adjustment of said retractor elements.

EDGAR J. POTH. 45
